John R. Sowers, 1608 E. Tucker, Compton, Calif. 90221

Original design application Oct. 16, 1964, Ser. No. 82,207,
now Patent No. 204,466, dated Apr. 19, 1966. Divided
and this application Nov. 22, 1965, Ser. No. 1,497

Term of patent 14 years

(Cl. D34—5)

FIGURE 1 is a rear elevational view of a putter head, showing my new design;

FIG. 2 is a top plan view thereof;

FIG. 3 is a front elevational view thereof;

FIG. 4 is an end elevational view taken from the right of FIG. 1; and

FIG. 5 is an end elevational view taken from the left of FIG. 1.

A portion of the putter shank with which the putter head is used, and illustrated in phantom lines in FIGS. 1, 3, 4 and 5 is for illustrative purposes only.

This is a division of application Ser. No. D. 82,207, filed Oct. 16, 1964, now Patent No. Des. 204,466.

I claim:

The ornamental design for a putter head or similar article, substantially as shown and described.
